WINDOW LIFT AND FASTENER

Filed Aug. 25, 1944

This is a continuation-in-part of my application for a patent filed on January 20, 1944, Serial No. 511,215, and for the reasons set forth in the original application, I claim:

UNITED STATES PATENT OFFICE

2,448,977

WINDOW LIFT AND FASTENER

Albert Hoekstra, San Antonio, Tex.

Application August 25, 1944, Serial No. 551,215

1 Claim. (Cl. 292—66)

2

This invention relates to windows, and has for one of its objects the production of a simple and efficient window pane-supporting means for a window, and means for conveniently holding the lower panel in an adjusted position, the window frame and window-pane-supporting means being so constructed as to eliminate the necessity of employing a conventional sash for supporting the pane.

Another object of this invention is the production of a simple and efficient means for holding the window pane in an adjusted position, and means for efficiently actuating this holding means.

Other objects and advantages of the present invention will appear throughout the following specification and claim.

In the drawing—

Figure 1 is a front elevational view of the window pane, showing the window pane and its supporting means in position;

Figure 2 is an enlarged front elevational view of the lower portion of the window frame and illustrating the manner of supporting the window pane of the lower panel and showing the means for holding the window pane in an adjusted position, certain parts being shown in section;

Figure 3 is an enlarged fragmentary sectional view taken on line 3—3 of Fig. 1;

Figure 4 is a vertical sectional view taken on line 4—4 of Figure 2;

Figure 5 is an enlarged sectional view taken on line 5—5 of Figure 2;

Figure 6 is a sectional view taken on line 6—6 of Figure 2.

By referring to the drawing, it will be seen that 10 designates the window frame which supports an upper panel 11 preferably comprising two vertical side panes 12 and a central pane 13. The central pane 13 may be adjusted transversely of the frame 10 as indicated by the arrow A for ventilation purposes, if desired. These panes 12 and 13 of the panel 11 may be supported in any desired manner without departing from the spirit of the invention.

A lower panel 14 is slidably mounted upon the frame 10, as shown, and this lower panel 14 comprises preferably a glass window pane 15, the side edges of which are slidably mounted in the vertical guide channels 16 of the side rails of the frame 10. A base rail 17 supports the lower edge of the window pane 15 and this base rail 17 is provided with a horizontal groove 18 in its upper edge into which the lower edge of the pane 15 is securely seated as shown in Figures 2, 3 and 4. A suitable sealing packing 19 may be carried by

the base rail 17 for engaging the outer face of the pane 15 to provide a weather seal, if desired.

A sash lift 20 is carried near one end of the base rail 17 as shown in Figure 2 to facilitate the lifting of the base rail 17. A pivoted sash lift 21 is carried near the opposite end of the base rail 17. This pivoted sash lift 21 constitutes a lever pivoted at 22, and is normally positioned at an incline to the longitudinal axis of the base rail 17. A latching rod 23 is pivotally secured to one end of the pivoted sash lift 21, as at 24, and this rod 23 is fitted in the socket 25 formed at one end of the base rail 17. The latching rod 23 extends longitudinally of the base rail 17 and normally projects beyond the end of the base rail 17. An aperture 26 is formed transversely of the rail 17 and communicates with the socket 25 so that the angularly extending end 27 of the rod 23 may connect to the pivoted sash lift 21, as shown in Figures 4 and 6. The aperture 26 is made of sufficient size as to permit of proper movement of the lift 21 and rod 23. A stop pin 28 extends transversely of the rail 17 and is adapted to engage the rod 23 and prevent the rod 23 from swinging in one direction as described in the following:

The side rails of the frame 10 are provided with a suitable number of spaced transversely extending pockets 29 which communicate with the channels 16 and extend away from the channels 16. These pockets 29 are adapted to receive the projecting end of the rod 23 for holding the panel 14 in a vertically adjusted position. A pocket 30 may be provided in the frame 10 to receive the projecting end of the rod 23 when the panel 14 is in its lowered or closed position.

When it is desired to lift the lower panel 14, the sash lift 20 is gripped by the right hand and the upwardly extending end 21^a of the pivoted sash lift 21 is pushed downwardly by the fingers or hand of the operator thereby drawing the rod 23 out of the pocket 30 and into the channel 16. When the panel 14 has been raised to the desired height, the downwardly inclined end 21^b of the pivoted lift 21 is pushed downwardly thereby extending the rod 23 into one of the pockets 29 in the side rail of the frame 10. The stop pin 28 carried by the base rail 17 will act as a fulcrum for the rod 23 and the weight of the sash by resting upon the rod 23 through the medium of the pin 28 will cause the rod 23 to be retained within the selected pocket 29 and support the panel 14 in a vertically adjusted position, or the position shown in dotted lines in Figure 1. The angularly extending end 27 of the rod 23 will bind upon the

lower portion of the aperture 26 and the rod 23 will in this manner be held in a set position to support the panel 14 in a desired open or raised position until an operator through the manipulation of the lever or pivoted lift 21 swings this pivoted lift 21 to a position to withdraw the rod 23 out of engagement with the selected pocket 29 when the panel 14 may be raised to a higher position or lowered to the closed position such as shown in Figure 2. It should be understood that it is necessary to have the pockets 29 formed only in one side of the frame and it should be understood that the rod 23 is merely a latch or supporting means and is not intended for a locking device. Any auxiliary locking device may be employed without departing from the spirit of the invention.

From the foregoing description it will be seen that the present window is not provided with a sliding sash such as the conventional window sash, but that the lower sliding panel 14 comprises only the base rail 17 which supports the glass pane 15 and that these are the only two parts of the lower panel exclusive of the locking or lifting mechanism. The edges of the base rail 17 abut against the sides of the frame 10 and the side edges of the glass pane 15 project into the channels 16 which are formed in the side rails of the frame 10. There are no weights, springs, or other mechanism employed, and because of the fact that the frame is not made up of a number of separate pieces as is the case with the conventional frame, swelling and binding will be reduced to a minimum or eliminated entirely. The device may be manufactured easily and economically and the frames could be shipped separately and the glass pane 15 is preferably of double strength, the metal parts being made of a suitable type of material which may be found of advantage. The device may be easily assembled and nailed into a building after the window frame and its component panels are assembled and may be utilized in wood as well as plastic, tile, brick or stone buildings.

A suitable sill S is preferably provided as a

base abutment for supporting the frame 10 and against which the lower edge of the base rail 17 may rest.

Certain detail changes in the construction of the device may be employed without departing from the spirit of the invention, so long as such changes fall within the scope of the appended claim.

Having described the invention, what I claim as new is:

A sash fastener comprising a support, a sash lift pivoted on the front surface thereof, said support having a socket formed therein and extending rearwardly from said front surface between the pivot point of said sash lift and the end of said support, said support having a slot formed therein and extending from the base of said socket through said end, said slot having two spaced walls and an inner third wall, a latching member pivoted to one end of said sash lift having a first portion extending through said socket and a second portion integral with the first portion and at right angles thereto and extending through said slot in a direction parallel to the front surface of said support, and a stop pin extending across said slot between the spaced walls thereof and at a substantial distance greater than the transverse dimension of the latching member from the third wall thereof and serving with said third wall to limit the transverse movement of said second portion of the latching member.

ALBERT HOEKSTRA.
